Primary Examiner — Jack Reickel*Assistant Examiner* — Russell Carnell Smith, Jr.(74) *Attorney, Agent, or Firm* — COOLEY LLP(57) **CLAIM**

The ornamental design for an earpiece, as shown and described.

DESCRIPTION

FIG. 1 is a front view of a first embodiment of the new design for an earpiece;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a front, upper, left perspective view thereof;

FIG. 8 is a front, upper, right perspective view thereof;

FIG. 9 is a front, lower, right perspective view thereof;

FIG. 10 is a front, lower, left perspective view thereof;

FIG. 11 is a rear, upper, right perspective view thereof;

FIG. 12 is a rear, upper, left perspective view thereof;

FIG. 13 is a rear, lower, right perspective view thereof; and,

FIG. 14 is a rear, lower, left perspective view thereof.
